APPARATUS FOR CHARGING RECEPTACLES

Cecil A. Hallam, Westfield, N. J., assignor to
 Western Electric Company, Incorporated, New
 York, N. Y., a corporation of New York

Original application September 4, 1931, Serial No.
 561,141. Divided and this application October
 12, 1932, Serial No. 637,452

3 Claims. (Cl. 207—1)

This invention relates to an apparatus for charging receptacles and more particularly to an apparatus for automatically charging the cylinder of a cable sheathing press.

5 This invention is a division of my copending application Serial No. 561,141, filed September 4, 1931.

When forming a lead alloy sheathing about a cable, one practice, after the completion of the 10 extrusion cycle, is to withdraw the cylinder completely from the ram before refilling the cylinder with fused alloy in preparation for the next extrusion cycle. The charge is sometimes introduced into the cylinder from a kettle or from 15 a supply conduit leading from a reservoir of fused alloy.

Objects of the present invention are to provide a simplified and improved apparatus for expeditiously charging receptacles.

In order to attain these objects the charging 20 material surrounds a closure member of a receptacle so that the material automatically flows into the receptacle when the member and the receptacle separate. Specifically the end of the ram of a cable sheath extruding press is maintained enveloped in a bath of molten lead alloy 25 which is contained free from the atmosphere in a covered receptacle so that the cylinder is recharged due to the partial vacuum produced therein and the force of gravity when the end 30 of the ram separates from the head of the cylinder.

A complete understanding will appear in the following detailed description taken in conjunction 35 with the accompanying drawing wherein like characters of reference indicate corresponding parts in the several views:

Fig. 1 is a partial elevational view of a cable sheathing press embodying the invention and 40 which may be used in practicing the improved method;

Fig. 2 is a transverse section taken along the line 2—2 of Fig. 1, and

Fig. 3 is a partial plan view taken along the line 3—3 of Fig. 2.

45 Referring to the drawing, an extruding press 10 of the kind employed in cable sheathing comprises a cylinder 11 disposed upon a movable head 12 of the press and a ram 13 the end of which passes down into the cylinder. The ram depends from a fixed head 14 which is supported by suitable columns 15.

A receptacle 16 contains the supply of fused 50 alloy, and through a circular aperture 17 in the bottom thereof the ram passes into an opening 18

of the cylinder. The receptacle is provided with a cover 19 to shield the molten alloy from the atmosphere, thereby retarding the tendency of the fused metal to oxidize. In addition the cover offers a readily accessible means to facilitate the removal of the dross which tends to accumulate on the surface of the molten alloy. The cover is suitably attached to the receptacle and is partially removed for the examination of the surface of the molten alloy and for the refilling of the receptacle. The cover is constructed so as to contain a circular aperture 20 which offers only sufficient clearance for the movement of the ram in the receptacle.

The circular aperture 17 is provided with a 15 beveled edge 21 to facilitate the flow of fused alloy from the receptacle into the cylinder and the bottom of the receptacle has an integral annular base 22 for fastening it to the head of the cylinder. The annular base of the receptacle is provided with a plurality of openings 23 appropriately spaced so that they fit upon a plurality of cap screws 24 similarly placed on the head of the cylinder. After the openings 23 engage the cap screws a suitable pressure applied along the periphery of the receptacle causes the cap screws to lock into the reduced portion of the openings. In order to prevent the fused alloy from escaping through the joint between the bottom of the receptacle and the head of the cylinder, an asbestos gasket 25 is employed. The receptacle is reinforced by members 26 welded to the outside thereof, and an additional support is supplied by a plurality of braces 27 appropriately distributed on the head of the cylinder 30 so as to set under the members 26.

For the initial charge the cylinder is brought to a position wherein the ram is inserted to its maximum depth. The fused alloy is introduced into the receptacle through a suitable conduit 40 leading from a melting furnace and is maintained in the molten state therein by any convenient heating means, not shown. It will be observed that the tight fitting cover is to remain on the receptacle at all times, except, of course, 45 for the infrequent periods required for the inspection of the surface of the molten alloy for the possible formation of dross and for the refilling of the receptacle.

The reciprocation of the cylinder is caused by 50 any suitable and usual means, not shown. As the head of the close-fitting cylinder separates from the end of the ram upon the descent of the cylinder, the fused alloy in the receptacle is drawn into the cylinder because of the partial 55

vacuum created therein and by the action of gravity upon the heavy alloy. When the maximum point in the withdrawal of the cylinder is reached, the head of the ram is still well immersed in the fused alloy bath and the cylinder is charged. The charge within the cylinder as well as the portion in lower section of the receptacle, which is awaiting use for subsequent charge is completely isolated from the atmosphere, and, simultaneously the fused alloy bath, which completely envelopes the ram-end, excludes air from entering into the cylinder. It is to be observed that in this manner the interior of the cylinder is isolated from the atmosphere thereby affording the best condition for the manufacture of an alloy sheathing with a smooth surface. Under the aforementioned isolation of the charge within the cylinder from air, the conditions for manufacturing are further improved due to the retardation of the tendency of the alloy to oxidize as it is introduced into the cylinder, the exclusion from the cylinder of the dross which tends to form on the alloy bath, and the elimination of the tendency toward the formation of blisters in the sheathing surface because of the incomplete removal of air from the cylinder. As the extrusion cycle is repeated the consumed alloy of the receptacle is replaced with a fresh supply through a conduit leading from a reservoir of the molten material so that the head of the fused alloy bath contained in the receptacle is maintained at a level which allows the operation heretofore described.

This apparatus substantially expedites the charging of the cylinder since the automatic charging thereof eliminates the period of time which was formerly consumed by the manual charging operation. It will be observed that the supply of molten alloy can be introduced into the receptacle without any loss of time since the refilling operation can be accomplished while the charge in the cylinder is held for partial solidification preparatory to the reciprocation of the cylinder. Additional improvements in the conditions for the manufacturing of protective sheathing for electrical cables are provided in the means for controlling the quantity of air in the cylinder and the tendency of the fused charge

therein to oxidize whereby the imperfections of blisters and cavities in the surface of the sheathing are eliminated.

While details of the construction of the apparatus have been given for the purpose of fully explaining the invention, it is obvious that these can be modified in various respects without departing from the spirit and scope of the invention as defined in the appended claims.

What is claimed is:

1. In an apparatus for charging an extrusion press cylinder having a cooperating ram normally retractable from the cylinder to permit charging of the same through the ram entrance aperture thereof, a receptacle for a bath of fused material supported upon the cylinder and having an aperture in the bottom thereof provided with a beveled edge for providing an entrance into the cylinder and aligned with the ram entrance aperture of the cylinder, and a cover for the receptacle to exclude the atmosphere therefrom.

2. In an apparatus for charging an extrusion press cylinder having a cooperating ram normally completely withdrawable from the cylinder to permit charging of the same through the ram entrance aperture thereof, a receptacle mounted on the cylinder for containing a bath of fused alloy of sufficient quantity to continually surround the working end of the ram during the entire period of withdrawal of the ram from the cylinder, and a cover for the receptacle, apertures being provided both in the cover and in the bottom of the receptacle in alignment with the ram entrance aperture of the cylinder for the passage of the ram therethrough.

3. A vertical extrusion press for metals comprising a container into which molten metal is charged at the upper end, the side walls of the container being in contact with the atmosphere, a ram in said container, means for producing relative vertical movement between said container and said ram to extrude metal and withdraw for charging, and a sealing and feeding vessel surrounding the ram and mounted on the upper end of the container, the lower portion of the vessel communicating with the space occupied by the working charge in the container.
